DESIGN FOR AN INSTRUMENT CASE

Phillip G. Clark, East Orange, N. J., assignor to
Weston Electrical Instrument Corporation,
Newark, N. J., a corporation of New Jersey

Application February 12, 1936, Serial No. 61,116

Term of patent 7 years

To all whom it may concern:

Be it known that I, Phillip G. Clark, a citizen of the United States, residing at East Orange, in the county of Essex and State of New Jersey, have invented a new, original, and ornamental Design for an Instrument Case, of which the following is a specification, reference being had to the accompanying drawing, forming part thereof, and wherein:

Fig. 1 is a front elevation of the instrument case showing my new design;

Fig. 2 is a side view; and

Fig. 3 is a plan view.

I claim:

The ornamental design for an instrument case, as shown.

PHILLIP G. CLARK.
